CLAIM

The ornamental design for a vehicle latch, as shown and described.

DESCRIPTION

FIG. 1 is a bottom, front, right side perspective view of a vehicle latch showing our new design;

FIG. 2 is a bottom view of the vehicle latch of FIG. 1;

FIG. 3 is a top view of the vehicle latch of FIG. 1;

FIG. 4 is a front side view of the vehicle latch of FIG. 1;

FIG. 5 is a rear side view of the vehicle latch of FIG. 1;

FIG. 6 is a right side view of the vehicle latch of FIG. 1;

FIG. 7 is a left side view of the vehicle latch of FIG. 1;

FIG. 8 is a bottom, rear, left side perspective view of a vehicle latch of FIG. 1;

FIG. 9 is a bottom, rear, right side perspective view of a vehicle latch of FIG. 1;

FIG. 10 is a top, front, right side perspective view of a vehicle latch of FIG. 1;

FIG. 11 is a top, front, left side perspective view of a vehicle latch of FIG. 1; and,

FIG. 12 is a top, left side perspective view of a vehicle latch of FIG. 1.

The broken lines illustrate portions of the vehicle latch which form no part of the claimed design.
